(57) **CLAIM**

The ornamental design for a system control panel, substantially as shown and described.

DESCRIPTION

FIG. 1 is a perspective view of a system control panel embodying the design of the present invention;

FIG. 2 is a front elevational view of the system control panel illustrated in FIG. 1;

FIG. 3 is a rear elevational view of the system control panel illustrated in FIG. 1;

FIG. 4 is a left side elevational view of the system control panel illustrated in FIG. 1;

FIG. 5 is a right side elevational view of the system control panel illustrated in FIG. 1;

FIG. 6 is a top view of the system control panel illustrated in FIG. 1; and,

FIG. 7 is a bottom view of the system control panel illustrated in FIG. 1.

In the drawings, the broken lines show elements of a system control panel and form no part of the claimed design.
